APPARATUS FOR ELEVATING AND DUMPING
THE CONTENTS OF CONTAINERSHoward C. House and Frederick F. House, Buffalo,
N. Y., assignors to Jacob House & Sons, Buffalo,
N. Y., a partnership

Application September 30, 1948, Serial No. 51,902

5 Claims. (Cl. 214—1.1)

1

This invention relates to apparatus for elevating and dumping the contents of containers and more particularly to such apparatus for lifting bags made of paper or cloth, the mouths of which have been opened, and partly inverting the bags at an elevated station so as to discharge the contents, such as sugar, over the elevated rim of a storage bin or hopper.

Another object of the invention is to provide such apparatus which will handle bags of any weight and eliminate the heavy manual work of filling high bins with the contents of such bags.

Another object is to provide such apparatus which is movable or portable and can readily be moved from place to place to operate in conjunction with different storage bins or hoppers.

Another object is to provide such apparatus which occupies little floor space and can be arranged close to the side of the bin or hopper to be filled.

Another aim is to provide such apparatus which lifts the bags to a high elevation and at this elevation inverts them sufficiently to dump the contents of the bag and substantially empty the same.

Another object is to provide such apparatus which discharges the contents of the bags fully without dropping the bag, which bag is returned in its normal upright position to floor level.

Another purpose is to provide such apparatus which is easily loaded, the bags being required to be lifted only a few inches from the floor and swung, in an upright position, directly into the carrier which elevates the filled bags.

Another object is to provide such apparatus which is balanced so that there is no danger of the structure overturning even when irregularities in floor slopes are encountered and in which the bag is also inverted by rotation about its center of gravity so as to require little power for this operation.

Another aim is to provide a carrier with counter-weighting so as to swing to a normally upright loading position during its rising and return movements along the elevator structure.

Another aim is to provide such apparatus which is light in weight and low in cost and composed of few parts which are of sturdy construction so that the apparatus will operate under conditions of severe and constant use without getting out of order or requiring repairs.

Other objects and advantages will appear from the following description and drawings in which:

Fig. 1 is a vertical front elevational view of apparatus for elevating and discharging bags of paper or cloth and constructed in accordance with the present invention.

2

Fig. 2 is a top plan view thereof.

Fig. 3 is an enlarged horizontal section taken on line 3—3, Fig. 1.

Fig. 4 is a side elevational view thereof.

5 Fig. 5 is a fragmentary enlarged vertical section taken on line 5—5, Fig. 4.

Fig. 6 is a vertical section taken on line 6—6, Fig. 1.

The apparatus forming the subject of the present invention comprises a movable or portable framework supporting a vertical movable carrier which normally swings to a generally upright position in which it can be conveniently loaded at the floor with a cloth or paper bag of sugar or the like, the mouth of the bag being opened. As the carrier reaches a predetermined elevation it is swung around the center of gravity of the filled bag to a partly inverted position so as to dump the sugar from the bag over the elevated rim 20 of a storage bin or feed hopper, the carrier being designed to retain the bag and to permit the emptying of substantially all of the contents thereof. On downward movement of the carrier it assumes its original upright position so that at 25 the loading station the empty bag can be readily removed and replaced with a filled bag.

The framework of the apparatus comprises a base part 10 constructed of side beams 11 which are of inverted L-shaped form in cross section and have their horizontal flanges projecting outwardly and having a rear top plate 12 which is also L-shaped in cross section, this plate being welded or otherwise secured to the horizontal flanges of the side beams 11 and having a vertical flange welded or otherwise secured to the rear ends thereof. The base 10 is shown as supported by four casters 13 suitably secured to the under sides of the horizontal flanges of the side beams 11, these casters permitting the structure to be 30 rolled from place to place to load different bins or hoppers or to be stored out of the way when not in use.

To the inner face of each of the side beams 11 is secured, as by welding, a vertical rail 15, these rails being of channel shape in cross section with their channels opposing each other. The connection between each rail 15 and its side rail 11 can be reinforced by an L-shaped bracket 16 suitably bolted to these parts and the upper ends of these rails are shown as connected by a cross bar 18. The structure is shown as strengthened by triangular plates 19 welded to the front and rear faces of the rails 15 and cross bar 18 and which also serve to support pulleys as herein-after described.

The bags are placed in a carrier indicated gen-

erally at 20 and which is normally arranged in the full line position shown in the drawings. In this position the pan has a rear wall 21 provided with a forwardly projecting rim including a bottom wall 22, side walls 23 and converging upper walls 24 which define an opening 25 at the upper end of the carrier which is less than the width of the bag but is of sufficient size to permit discharge of the contents from the bag when the pan or carrier is partly inverted. In the loading position the pan 20 is arranged, in the full line position shown, at the bottom of the structure and to retain the bag in the carrier when it is inverted, a plurality of cleats 26 preferably of rubber are fastened to its rear wall 21. The carrier 20 is also provided on its bottom wall 22 with a counterweight 27 to bring the pan to the normal full line position shown when the same is released. In this position a pair of guide rollers 28 on the side walls 23 of the carrier engage and ride along the outer faces of the front flanges of the channel shaped guide rails 15.

The carrier is guided for vertical movement along the side rails 15 and for this purpose is provided on its opposite sides with a pair of stub shafts 29 which project outwardly from the side walls 23 of the carrier in axial alignment with each other and are journaled in travelers or sliders 30 arranged in and guided by the opposing channels of the side rails 15. The stub shafts 29 are fixed to the carrier 20 through a U-shaped holder 31 which embraces the front and side walls 21, 23 of the carrier and is suitably secured thereto and to the legs of which the stub shafts 29 are secured to project outwardly from the side walls 23 of the carrier. The end of each of the stub shafts 29 is journaled in a bearing 32 secured to the corresponding traveler 30, each traveler being provided with a pair of parallel flanges 33 which fit within the side flanges of the corresponding channel shaped rail 15 and with a pair of end flanges 34 which ride against the edges of the flanges of the corresponding channel rail 15. Between the carrier 20 and the corresponding side rail 15 each of the stub shafts 29 carries a pulley 35 which is freely rotatable thereon and which can be held in place by suitable collars 36, 38 and 39 as shown.

The carrier 20 is raised and lowered along the side rails 15 by a reversible electric motor 40 mounted on the top cross plate 12 of the base of the framework and driving a pair of drums 41 and 42. One end of an elevating line or cable 43 is fixed to the drum 41 and extends upwardly over a pulley 44 loose on a stub shaft 45 carried by the triangular reinforcing plates 19 at the corresponding side of the framework. From this pulley 44 the elevating line 43 extends downwardly under the pulley 35 on the corresponding side of the carrier 20 and thence this or cable extends upwardly over a pulley 46 at the forward end of the stub shaft 45. From the pulley 46 the line or cable 43 extends horizontally along the front face of the cross bar 18 to a pulley 48 loosely mounted on the forward end of a stub shaft 49 carried by the corresponding triangular reinforcing plates 19. From the pulley 48 the line or cable extends downwardly under the pulley 35 at the corresponding side of the carrier 20 and from this pulley the cable extends upwardly over a pulley 50 mounted on the rear end of the stub shaft 49. From this pulley 50 the cable extends horizontally across the rear side of the cross bar 18 to a pulley 51 mounted

on the rear end of the stub shaft 45 and thence this cable extends downwardly and is attached to the drum 42. In order to tighten the cable 43 a turnbuckle 52 can be provided in its horizontal stretch between the pulleys 46 and 48.

Suitable limit switches (not shown) can be provided for limiting the upward and downward movements of the pan or carrier, the electrical circuit also preferably including the usual stop and start switch so that the movement of the carrier can be halted and restarted at any point of its travel.

In order to tip the carrier 20 to a partly inverted position when it reaches the stop of the elevator structure, a line or chain 56 is secured by an eye bolt 58 to the front wall 21 of the pan near the upper or discharge end thereof and is secured by an eye 59 to the rear end of the base 10 of the framework. This line 56 is shorter than the length of travel of the carrier along the rails 15 and hence when the carrier approaches its elevated dumping station, the upper end of this pan or carrier is restrained so as to cause it to swing to the dumping position shown by dotted lines in Fig. 4.

In the operation of the apparatus a heavy paper or cloth bag (not shown), of, say, sugar, is opened at its upper end and is lifted and swung into the generally upright carrier 20 which is positioned near the floor as shown in full lines in the drawings. The weight of the bag rests principally upon the bottom 22 of this carrier and the bag leans against the cleats 26 on the rear wall 21 of this carrier. The operator then presses the start button (not shown) to energize the motor 40. This motor rotates the drums 41 and 42 so as to wind up the opposite ends of the cable 43. Since this cable passes over the overhead pulleys 44, 46, 48, 50 and 51 on the framework and under the pulleys 35 on the carrier, the shortening of the effective length of this cable 43 draws upwardly the carrier pulleys 35 and moves the carrier 20 upwardly, this movement being permitted by the travelers 30 which are guided for upward movement in the channels of the vertical guide rails 15. While moving upwardly the carrier 20 maintains the position shown by full lines, its rollers 28 riding along the forward faces of the guide rails 15.

As the carrier approaches the upward limit of its travel the chain 56 is drawn taut and since this restrains the upper part of the carrier 20 against further upward movement while the upward movement of its bottom part continues, the carrier is caused to tip rearwardly. As the carrier continues its upward movement this tipping is increased until the carrier assumes the partly inverted position shown by dotted lines in Fig. 4. When the carrier reaches this position the motor 40 is de-energized, either manually or by a limit switch (not shown).

In this partly inverted position of the carrier 20 as shown by dotted lines in Fig. 4, the contents of the bag spill out of its open mouth into the elevated bin or hopper (not shown) into which the contents of the bag are to be discharged. However, the bag itself, if of paper, is prevented from sliding out of the carrier, both because of the restraining effect provided by the cleats 26 and also because the shoulders of the bag at the opposite sides of its open mouth are engaged by the converging parts 24 of the side walls 23 of the carrier. If the bag is of cloth and hence less stiff than a paper bag, the bag is

retained against sliding into the bin or hopper largely by the cleats 26.

After the bag has been emptied the operator reverses the motor 40 so as to unwind the opposite ends of the cable 43 from the drums 41 and 42. This increases the effective length of this cable and permits the carrier to descend by gravity with its travelers 30 moving along and guided by the opposed channels of the side rails 15. During this downward movement the counterweight 27 causes the carrier to swing counterclockwise as viewed in Fig. 4, this swinging being permitted by the lowering of the axis of rotation of the carrier with reference to the point of attachment 58 of the cable 56. After this axis passes below this point of attachment 58 the counterweight 27 causes the rollers 28 to engage the forward faces of the guide rails 15, the carrier thereby being brought to the angular position shown by full lines in the drawings and the carrier continuing its descent while so positioned. When the carrier reaches the bottom of the rails the motor 40 is de-energized, either manually or by a limit switch (not shown) and the empty bag is removed therefrom and replaced with a filled bag to repeat the operation. It will be noted, however, that if the motor is not de-energized exactly at the lower limit of movement of the carrier, the only effect is to start to rewind the opposite ends of the cable 43 on the drums 41 and 42 to start an upward movement of the carrier.

From the foregoing it will be seen that the present invention provides a very simple apparatus for elevating and dumping the contents of containers, such as heavy bags, which can be readily moved from place to place, which is free from the danger of toppling even when uneven floors are encountered, and which is safe and positive in its action and serves substantially to completely empty the contents of the containers at a high elevation and without dropping the containers into the elevated bin or hopper into which the contents are dumped.

We claim.

1. Apparatus for elevating and dumping the contents of containers, which comprises a supporting structure having generally parallel and vertical spaced guide members, a traveler guided for vertical movement along each of said guide members, a carrier for said containers interposed between said guide members and having a rear wall and a rim projecting forwardly from the bottom and sides of said rear wall to provide bottom and side walls, means pivotally connecting the side walls of said carrier with said travelers to swing about a generally horizontal axis, means for moving said travelers up and down said guide members, means restraining the movement of the upper part of said carrier on approaching the upper limit of movement of said travelers to swing said carrier about said axis and partly invert said container to dump the contents thereof, and means arranged to retain said container on said carrier while dumping said contents, comprising inwardly converging portions provided at the upper ends of said side walls and arranged to engage said container and a series of transverse cleats secured to the forward face of said rear wall and engageable with said container.

2. Apparatus for elevating and dumping the contents of containers, which comprises a supporting structure having generally parallel and vertical spaced guide members, a traveler guided

for vertical movement along each of said guide members, a carrier for said containers interposed between said guide members and having a rear wall and a rim projecting forwardly from the bottom and sides of said rear wall to provide bottom and side walls, coaxial stub shafts fixed to said side walls and projecting horizontally outwardly therefrom, a horizontal bearing in each traveler and receiving the corresponding stub shaft, a pulley loose on each of said stub shafts, overhead pulleys carried by said guide members adjacent to the upper ends thereof, an elevator line passing generally parallel with said guide members under said pulleys on said stub shafts and over said overhead pulleys, means arranged to decrease and increase the effective length of said elevator line to raise and lower said carrier, and means restraining the upper part of said carrier on approaching the upper limit of movement of said travelers to swing said carrier about said axis and partly invert said container to dump the contents thereof.

3. Apparatus for elevating and dumping the contents of containers, which comprises a movable base, a supporting structure having generally parallel and vertical spaced guide channel bars arranged with their channels opposing each other and a cross bar connecting the upper ends of said channel bars, a traveler movable along each of said bars and having a pair of parallel flanges arranged inside of and guided along the opposing faces of the flanges thereof and a pair of coplanar flanges guided along the edges thereof, a carrier for said containers interposed between said guide bars, means pivotally supporting said carrier on said travelers to swing about a generally horizontal axis arranged adjacent the center of gravity of the carrier loaded with one of said containers, means arranged to move said travelers up and down said guide bars, means restraining the movement of one part of said carrier on approaching the upper limit of movement of said travelers to swing said carrier about said axis and partly invert said container to dump the contents thereof, and means on said carrier and arranged to retain the container thereon while dumping said contents.

4. Apparatus for elevating and dumping the contents of containers, which comprises a movable base, a supporting structure having generally parallel and vertical spaced guide channel bars arranged with their channels opposing each other and a cross bar connecting the upper ends of said channel bars, a traveler movable along each of said bars and having a pair of parallel flanges arranged inside of and guided along the opposing faces of the flanges thereof and a pair of coplanar flanges guided along the edges thereof, a carrier for said containers interposed between said guide bars and having a rear wall and a rim projecting forwardly from the bottom and sides of said rear wall to provide bottom and side walls, coaxial stub shafts fixed to said side walls to project horizontally outwardly therefrom and journaled in said travelers, means connected with said stub shafts and cross bar and arranged to move said travelers up and down said guide bars, and means restraining the upper part of said carrier on approaching the upper limit of movement of said travelers to swing said carrier about said axis and partly invert said container to dump the contents thereof.

5. Apparatus for elevating and dumping the contents of containers, which comprises a movable base, a supporting structure having gener-

ally parallel and vertical spaced guide members and a cross bar connecting the upper ends of said guide members, a traveler guided for vertical movement along each of said guide members, a carrier for said containers interposed between said guide members and having a rear wall and a rim projecting forwardly from the bottom and sides of said rear wall to provide bottom and side walls, means pivotally connecting the side walls of said carrier with said travelers to swing about a generally horizontal axis, a loose pulley on each side of said carrier coaxial with said pivotally connecting means, overhead pulleys carried by said cross bar, an elevator line passing generally parallel with said guide members under said pulleys on said carrier and over said overhead pulleys, a pair of drums on said base, means connecting the opposite ends of said elevator line to said drums to be wound thereon in one direction of rotation of said drums, a motor on said base

and driving said drums, and means restraining the upper part of said carrier on approaching the upper limit of movement of said travelers to swing said carrier about said axis and partly invert and dump the contents thereof.
